UNITED STATES PATENT OFFICE.

NELSON C. NEWELL, OF SPRINGFIELD, MASSACHUSETTS.

BUTTON.

SPECIFICATION forming part of Letters Patent No. 273,133, dated February 27, 1883.

Application filed November 15, 1882. (No model.)

To all whom it may concern:

Be it known that I, NELSON C. NEWELL, a citizen of the United States, residing at Springfield, in the county of Hampden and State of Massachusetts, have invented new and useful Improvements in Buttons, of which the following is a specification.

This invention relates to improvements in buttons, and in methods of uniting the parts thereof when said parts consist of several pieces of more or less rigid materials, the object being to provide improved means for combining in a button a face of pearl with a surrounding border of contrasting hard material, such as hard rubber or other similar substance, or vice versa, or in combining glass faces or borders with other contrasting substances, and to provide such improved means for securing said rigid materials together as result in a secure fastening thereof without danger of breaking the parts in process of manufacture.

In the drawings forming part of this specification, Figure III is a transverse section of a button embodying my invention. Fig. IV is a plan view of the back of said button. Fig. II is a transverse section of the button-center. Fig. I is a like view of the button back or shell, and Fig. V is a side and a plan view of the uniting-eyelet adapted to be used with said back and center.

In the drawings, *b* is the button-center. *a* is the back or shell, and *d* is the uniting-eyelet.

In making the centers or face parts *b* of the improved buttons herein described and shown, any suitable hard materials similar to those above mentioned, or hard woods may be used, and said centers are provided with a perforated or other suitable shank, *e*, for the usual purpose of securing the button thereby to a garment, and surrounding said shank in the body of said center *b* is formed an undercut groove or chamber, *c*. Said shank may be either integral with said center or be suitably secured to it. It is obviously not essential to the objects of this invention that said center *b* and said back or shell *a* be of circular form, since other shapes corresponding properly with each other may be adopted, according to the taste of the manufacturer. The shell *a* is made to fit onto the back of the center *b*, and has a central perforation, through which

the shank *e* passes, as shown in Fig. III, and a shallow groove is made around the border of said perforation, as shown in Fig. I.

The above-described center piece, *b*, and shell *a* are secured one to the other by means of a peculiarly-constructed eyelet, *d*. Said eyelet has a body of cylindrical form, having therein one or more slots, *i*, and a flange, *o*, surrounding one end and standing at an incline to said body, said flange *o* being provided with one or more slots, *v*, from its edge toward said cylindrical body *n*.

The above-described parts—*i. e.*, the center *b*, back or shell *a*, and eyelet *d*—are united as follows: The flange *o* of the eyelet, when the latter is placed on the shank *e* and pressed toward the rear side of the center *b*, enters the groove *c* in the latter, and by continuing to force the eyelet toward said groove the flange *o* spreads, and thereby said eyelet becomes firmly locked to the center *b*, its body *n* surrounding the shank *e*. The back or shell *a* is now placed upon the rear side of said center, and the edge of the body *n* of the eyelet, which projects through said shell, is bent outward and forced against the latter and into the said groove adjacent to said shank, thus firmly securing said parts together in the form of a button, as shown in Fig. III. Fig. IV illustrates the appearance of the flange, which is formed upon the end of said eyelet by bending the edge of said body *n* outward and against the shell *a*. The construction of said eyelet with the inclined slotted flange *o* provides for easily forcing and securing it in the undercut groove *c*, and its slotted body permits of turning said flange against the shell without danger of breaking the latter by lateral pressure, since said body is not rigid transversely.

If desired, a thin washer, of cloth or similar material, may be placed between the shell *a* and center *b*, or between the outer flange of the eyelet and the shell, or both, before "heading-down" the eyelet, for the purpose of obviating any danger there may be of breaking any part from any lack of elasticity when the eyelet is finally flanged, as above described.

What I claim as my invention is—

1. An improved button, consisting of a center having a shank on its rear side and an undercut groove therein, surrounding said

shank, of a perforated shell, substantially as described, and of an eyelet, substantially as described, adapted to engage in said groove in said center and to engage with said shell, 5 all as set forth.

2. A button-center having a shank on its rear side and an undercut groove therein, surrounding said shank, a perforated shell to fit upon the back of said center, and a uniting-

eyelet having a slotted cylindrical body adapted to engage with said shell, and a slotted flange thereon adapted to engage within said groove, all combined substantially as set forth.

NELSON C. NEWELL.
